UNITED STATES PATENT OFFICE.

EUGENE A. CRAWFORD, OF PAWTUCKET, RHODE ISLAND.

DESIGN FOR A BADGE.

SPECIFICATION forming part of Design No. 18,407, dated June 26, 1888.

Application filed May 15, 1888. Serial No. 274,001. Term of patent 7 years.

To all whom it may concern:

Be it known that I, EUGENE A. CRAWFORD, of Pawtucket, in the county of Providence and State of Rhode Island, have invented and 5 produced a new and original Design for a Badge; and I do hereby declare the following specification, taken in connection with the accompanying illustrations, to be a description thereof.

10 In the accompanying drawings, Figure 1 represents a face view of the badge embodying the design. Fig. 2 shows a face view of the panel and its border with convex corners. Fig. 3 shows a face view of the panel and its 15 border with concave corners.

The design consists in the representation of a cock or rooster, A, which is shown as standing upon a base, a, in the form of a portion

of the branch of a tree. Upon the body of the rooster is arranged or shown a panel, B, 20 having a border, b, surrounding the same. In Fig. 1 this panel and border are shown as having square corners; but the corners thereof may be convex, as shown in Fig. 2, or concave, as shown in Fig. 3.

25 What I claim, and desire to secure by Letters Patent, is—

The design for a badge herein shown and described, consisting in the representation of a cock or rooster standing upon a base, a, and 30 having a panel, B, in the surface of its body, surrounded by a border, b.
